[57] CLAIM

The ornamental design for an isle lighting assembly, as shown and described.

DESCRIPTION

FIG. 1 is a top perspective view of an isle lighting assembly showing my new design;

FIG. 2 is a bottom perspective view thereof;

FIG. 3 is a right side elevational view thereof on an enlarged scale;

FIG. 4 is a left side elevational view thereof on an enlarged scale;

FIG. 5 is a top perspective view of a second embodiment of my new isle lighting assembly;

FIG. 6 is a bottom perspective view thereof;

FIG. 7 is a right side elevational view thereof on an enlarged scale;

FIG. 8 is a left side elevational view thereof;

FIG. 9 is a top perspective view of a third embodiment of my new isle lighting assembly;

FIG. 10 is a bottom perspective view thereof;

FIG. 11 is a right elevational view thereof on an enlarged scale; and

FIG. 12 is a left elevational view thereof on an elongated scale.
